UNITED STATES PATENT OFFICE.

FRANK VOIGTMANN, OF CHICAGO, ILLINOIS.

FUSIBLE LINK.

1,017,715.

Specification of Letters Patent. Patented Feb. 20, 1912.

Application filed November 16, 1908. Serial No. 462,954.

To all whom it may concern:

Be it known that I, FRANK VOIGTMANN, a citizen of the United States, residing at Chicago, in the county of Cook and State of Illinois, have invented certain new and useful Improvements in Fusible Links, of which the following is a specification.

This invention relates to improvements in fusible links of the general type employed 10 for automatically releasing fire doors, windows, etc., whenever the temperature rises above a predetermined height.

The salient object of the present invention is to provide a link which while amply 15 strong to sustain the draft or pull thereon is more sensitive to heat and rises to the predetermined releasing temperature more quickly than links of the construction now in common use.

20 Subordinant objects of the invention are to provide a construction which is of extremely low cost and the parts of which may be accurately united by careless or unskilled labor.

25 The invention consists in the matters hereinafter described, and more particularly pointed out in the appended claims.

In the drawing—Figure 1 is a plan or top side view of a link embodying my invention;

30 Fig. 2 is a central longitudinal section; Fig. 3 is a central transverse section.

In constructing my improved link, I employ sheet metal of a relatively thin gage,—thinner than would be sufficient to sustain

35 the mechanical stresses, except for the fact that the two members are overlapped and dished together as to the chief portions of the link in such manner as to combine the strength of the two parts. As an example,

40 I prefer to employ for making a link $1\frac{1}{2}$ inches long, and capable of safely sustaining a draft up to 150 pounds, sheet bronze of thirty gage. Each link is composed of two stampings, as 1 and 2, which may be,

45 and preferably are, exact counterparts of each other; each stamping comprising, in the preferred embodiment shown, a mutilated main central ring portion 3 and an unmutilated smaller ring-shaped loop or eyelet 4 formed integrally with the main ring. The

50 main ring of each member is cut away at its side diametrically opposite the loop or eyelet 4, as indicated at 5, in such manner that when the two link members are placed together with their central main bodies in register. *i. e.* nested together, the loops or

eyelet portions 4 will project beyond the overlapped portions at each end. The overlapped portions obviously when soldered together combine to a large extent the strength 60 of both members, and in order that the eyelet portions which are not overlapped may be approximately as strong as the overlapped portions, I reinforce these smaller rings by eyeleting the openings thereof 65 with metal eyelets, as 6; these eyelets being provided with broad underlying flanges 7 which fit inside the concave portions of the members 4 while their upper edges are clamped over the peripheries of the opening, 70 as indicated at 8.

As one of the most important features of the present invention I resort to a method of soldering the link members together which I have discovered, and which has been found 75 to make the link far more sensitive to heat and more uniform in its fusing temperature than the links of the prior art. This method of soldering referred to consists in first properly cleaning the members of the link, 80 so that solder will readily adhere, by any suitable means, as for example by cleansing with a proper acid, then assembling the links in proper relation to each other, and, while holding the members pressed together 85 with a suitable tool, dipping them momentarily bodily in a bath of the solder, withdrawing them and immediately plunging the link in water or other suitable chilling medium. 90

The tool by which the link members are held while being submerged or dipped in the bath of molten solder may conveniently be a pair of tongs or pincers provided with pointed teeth or jaws, so that their points 95 of engagement with the link are small and the solder, therefore, permitted to cover practically the entire surface of the device. The dipping of the links into a cooling bath while possibly not essential to good results, 100 nevertheless results in solidifying the solder while it is evenly spread upon the parts and precludes its tendency to creep or gather into lumps at various points while solidifying slowly. This step of the process, therefore, renders the links more uniform as to their fusing points. These links in practical use usually become coated with soot, dust, etc., and it is the practice of underwriters to approximate conditions of practical use when testing such links by artificially coating them with calcimine, white- 110

wash or some analogous wash, and allowing them to dry before subjecting them to the fusing test. Such tests have demonstrated beyond question of doubt that the links constructed as described herein, and soldered by dipping them in a bath of molten solder, are many degrees more sensitive than links of the prior art, and are very considerably more sensitive than links constructed identically as described, except that they are simply soldered together in the usual way, *i. e.*, by applying solder to the meeting joints only. I am unable to account with certainty for this fact, but it may be due to one or more of the following causes, *viz*: by reason of the tendency of the fusing action to spread rapidly through the solder as soon as it begins to fuse at any one point, it may be that the exposure of so large an area of solder insures that some one or another will begin to fuse at an earlier stage than would otherwise be the case and that the entire fusion follows more quickly thereafter, or by reason of the manner in which the parts are held together while being dipped in the molten bath and chilled promptly after removal, the film of solder may be considerably thinner than that secured by ordinary methods, and for this reason the link made more sensitive, or the conductivity for heat of the film of solder may be greater than that of the underlying harder metal, and because of the larger surface of solder exposed to the heat, the fusing promoted.

35 While I have herein shown and described a preferred embodiment of the invention, and shown a construction which possesses in the mere matter of structure well defined improvements over the links of the prior art, nevertheless within the broader scope of the invention it may be otherwise embodied without departing from the spirit thereof. Accordingly I have claimed the device both broadly and specifically.

45 I claim as my invention:

1. A fusibly-separable link composed of two relatively thin sheet metal members, partially overlapped and united by a film

of solder extending between them, the overlapping portions being stamped into similar 50 intaglio-relief-surface patterns and internested, and the non-overlapped apertured ends of the device provided with metal reinforcements.

2. The combination with two thin sheet-like members partially overlapped and internested as to their overlapping portions and forming when united a thin relatively flat sheet-like link, said members being provided at their free outer ends with closed 60 loop portions, and a film of solder incasing the exterior of said links, and extending between and uniting the overlapping portion.

3. A fusibly-separable link composed of 65 two thin sheet metal members, partially overlapped and united by a film of solder lying between them, the overlapping portions being stamped into similar intaglio-relief surface patterns and internested, and 70 the openings in the extremities of the link reinforced by eyelets.

4. A fusibly-separable link composed of two substantially identical thin sheet metal members, each comprising a generally ring-shaped main body and a generally ring-shaped terminal loop, each ring portion being stamped into concavo convex form in radial section, the main bodies of the two members being overlapped and internested 80 and united by a film of solder.

5. A fusibly-separable link composed of two thin sheet metal members, each comprising a generally ring-shaped main body and a smaller generally ring-shaped terminal 85 loop, each ring-shaped main body being stamped into concavo convex form in radial section, the main bodies of the two members overlapped and internested, and the parts united by a film extending between the overlapped portions and covered with a coating 90 of solder.

FRANK VOIGTMANN.
